GARMENT BAG

Albert J. Roth, Manchester, Conn.

Application October 26, 1937, Serial No. 171,036

6 Claims. (Cl. 206—7)

This invention relates to improvements in garment bags and more particularly to that type of bag having an open bottom, through which a garment on a hanger is inserted therein, and an opening at the top through which the hook of the garment hanger projects.

It is well known that the application of such bags over a garment is a very tedious and inconvenient operation and that it is very difficult to apply the bags over a garment without tearing them.

Various means have been heretofore devised for aiding in the operation of applying such bags over a garment in such places as dry cleaning establishments. Other means have been devised for use with each individual bag, but such means have been designed to provide only for a single application of the bag; it being accepted that the bag was to be applied over the garment only temporarily and that when the garment was removed therefrom the bag would not be used again.

An object of my invention is to provide a bag having means which are a permanent part of the bag so that the said means may be used repeatedly for aiding in inserting a garment into the bag or removing it therefrom.

Other objects and advantages of my invention may be clearly understood from the following description and from the accompanying drawing in which:

Figure 1 is a front elevational view of a garment bag embodying my invention.

Figure 2 is a view in vertical section thereof on line 2—2 of Figure 1.

Figure 3 is a similar view showing a modified form of a bag embodying my invention.

Figure 4 is a front view of the said modified form illustrating one manner in which the same may be used.

As illustrated in the drawing, the numeral 5 denotes a garment bag of a conventional form which is usually constructed of paper and which is open at the bottom 6 and has an opening 7 at the top thereof through which the hook of a garment hanger may project so that the garment, together with the bag thereover may be hung in a convenient manner.

My invention consists of providing a tape, or cord 8 of any suitable material, which is secured at one end thereof, as at 9, to the outside of the bag and at a distance from the opening 7. The said tape extends upwardly from the point at which it is secured to the bag, downwardly through the opening 7, through the bag, and

ends in a loop 10 which projects below the bottom 6.

I prefer to extend the upper portion of the tape 8 to a distance above the top of the bag so that it will form a loop 11 which will facilitate the use of said tape in the manner to be hereinafter described.

As illustrated in Figure 1, the end 9 of the tape is fastened to the bag by means of a sticker 12 which consists of a small sheet of paper, or other suitable material, having an adhesive applied at one side thereof by means of which the same is secured upon the surface of the bag and to the end of the tape 8. If preferred, the said tape may be secured also by means of wire clips such as 13. The loop 10 at the lower end of the tape may be provided by doubling the end thereof and tying a knot therein as indicated at 14. However, the said loop may also be formed, as illustrated in the modified form illustrated in Figures 3 and 4, by doubling the tape for the entire length thereof and securing the two ends together to the bag.

In the use of my invention, the bag is applied over the garment which is usually supported on a hanger having a hook as indicated at 15. The said hook is hung on the loop 10 at the lower end of the tape or cord and the tape is then pulled upwardly, by means of the downwardly depending portion of the loop 11, thus raising the garment into the bag and at the same time lowering the bag over the garment. When the bag has reached its proper position over the garment, the hook 15 will extend through the opening in the top thereof and the tape will be in a position wherein it will hang downwardly on the outside of the bag and may remain in said position during the time that the said bag remains over the garment. When the garment is to be removed from the inside of the bag, the tape 8 will be already in position for use and the said garment may be removed by an operation which is simply the reverse of that above described.

If desired, my invention may be used, as illustrated in Figure 4 of the drawing, by hanging the bag over a supporting member 16, by means of the loop 11. The garment is then hung to the tape in the above described manner and the tape is pulled downwardly by its upper end, thus pulling the tape up around the support, raising the garment and, at the same time, lowering the bag over it.

It may readily be seen, that when the tapes or cords of certain materials are used, the loop 11 as shown in the drawing, may not be present

at all times for the reason that the tape 8 can easily drop down within the bag so that the loop 11 will be eliminated. The said loop, however, is readily provided by simply making the tape 5 long enough so that when the upper end of the same is pulled upwardly, with one hand, to form the said loop, the loop 10 at the bottom end of the tape will still project below the bottom of the bag so that the hook 15 of the garment hanger can be inserted therethrough with the other hand.

I claim:

1. A garment bag of the character described having an open bottom, an opening in the top thereof and a tape or cord permanently secured 15 to the outside of said bag and extending downwardly therethrough to a point below the bottom thereof.
2. A bottom-less bag of the character described having an opening in the top thereof and a tape or cord secured to the outside of said bag and extending downwardly through said opening.
3. A bottom-less bag of the character described having an opening in the top thereof, and a tape or cord secured to said bag at the

outside thereof and at a distance from the said opening, the said tape or cord extending upwardly on the outside of said bag and downwardly through said opening.

4. A bag of the character described having an open bottom and an opening in the top thereof, a tape or cord secured thereto at the outside of the bag and at a distance from the said opening, the said tape or cord extending upwardly on the outside of said bag and downwardly through 10 said opening and having a loop projecting below the bottom of said bag.

5. A bottom-less garment bag of the character described having an opening therein and a looped tape or cord secured to the outside of said bag 15 by its ends and extending downwardly through said opening.

6. A garment bag of the character described having an open bottom and an opening in the top thereof and comprising a tape or cord permanently secured thereto at the outside thereof, the said tape or cord being adapted to hang 20 downwardly between the sides of said bag and to a point below the bottom thereof and means on said tape or cord for attaching a hook thereto. 25

ALBERT J. ROTH.
